**HAND LIGHT IN COMBINATION WITH
FLASHER UNIT**

Arthur G. Davis, Marlboro, Mass., assignor to Koehler Manufacturing Company, Marlboro, Mass., a corporation of Massachusetts

Filed July 14, 1958, Ser. No. 748,342

6 Claims. (Cl. 340—366)

This invention relates to electrical lighting equipment and, more particularly, to a portable hand light of the dry-cell battery operated class with which is combined a signal accessory.

It is a principal object of the invention to provide an improved hand light which is characterized by long operating life combined with a maximum of efficiency and portability.

Another object of the invention is to combine a special light bulb and reflector assembly with a dry-cell battery and cover in a novel manner to provide for unique replaceability features.

Still another object of the invention is to devise a combination hand light and warning signal light which may be readily converted to intermittent flasher operation.

The nature of the invention and its objects will be more fully understood and appreciated from the following description of a preferred embodiment of the invention selected for purposes of illustration and shown in the accompanying drawings in which:

FIG. 1 is a view in side elevation of the hand light of the invention with a signal accessory attached in an operative position;

FIG. 2 is an elevational view showing the structure indicated in FIG. 1 by further illustrating the signal accessory in a disconnected position;

FIG. 3 is a vertical cross-sectional view taken approximately on the line 3—3 of FIG. 4;

FIG. 4 is a plan cross-sectional view taken on the line 4—4 of FIG. 2;

FIG. 5 is a modification of warning signal light; and

FIG. 6 is a view partly in cross section showing the light of FIG. 5 with an extension conductor in a stored position.

In accordance with the invention I have devised a hand light and signal accessory combination which is based on the novel concept of utilizing a battery member of the dry-cell type as a hand light base and further utilizing the battery terminals as threaded fastening posts for solidly anchoring thereto a dual light source unit. An important feature of this combination is a pair of special threaded fastening caps which can be engaged with the threaded terminal posts by a simple thumb and finger turning action to obtain a suitable securing action of the parts to one another. Each of these threaded fastener caps is formed with an annular bore in which may be received electrical contact elements for energizing through the battery a signal accessory.

In the structure shown in the accompanying drawings, numeral 2 denotes a dry-cell battery which may, for example, comprise a rectangular shaped member capable of providing a stable seating base at its bottom surface so that the battery may be disposed and positioned in an upright position when so desired.

At its upper side the battery is formed with a rim 4 which defines a recessed top area. From this top area projects threaded battery terminals 6 and 8 best shown in FIG. 3. Arranged to seat on this rim 4 in spaced relation to the top area is the light source unit S of the invention which comprises essentially an enclosure body of a somewhat similar rectangular shape as the battery although slightly larger in over-all dimension so as to

2

provide a protective over-hang as will be observed from an inspection of FIG. 1.

The light source unit S is formed with a recessed light supporting part 10 at one end of which is solidly mounted by welding, or other suitable means, a reflector housing element 12 which is recessed at 12a to provide for a slight over-hang as best shown in FIG. 2. The reflector housing 12 is fitted with a retaining rubber ring 14 which extends all the way around the housing and operates with or without a bezel ring 16 to adjustably secure together a lens 18 and a reflector 15.

In the reflector housing 12, at its opposite side, is a cylindrical opening 20 through which extends a bulb socket 22 in which is removably secured a bulb 24. The socket 22 is slidable in the reflector 15 and has its inner end solidly secured to one leg of an L bracket 26, the opposite leg of which is slidably supported against an adjacent wall surface 27 of the member 10. This bracket serves as a focussing adjustment member and may be secured in a desired focussing position by tightening a thumb nut 28 having a threaded extremity which passes through a slot in the wall 27 and is threaded into the leg of the bracket as best shown in FIG. 4.

In the preferred form of my invention I combine with the light source unit S described, a special electrical contact and conductor arrangement for energizing the bulb 24 and simultaneously providing means for supporting and electrically energizing a second signal accessory light A. This signal accessory light A may be of intermittent flasher type of conventional nature and equipped with a red signal lens A1.

Considering in further detail the electrical means for thus energizing both the bulb 24 and flasher light A, attention is directed to FIGS. 3 and 4. As noted therein an electrical conductor 30 extends through the socket 22 into electrical contact with the base of the bulb 24. At its opposite end the conductor 30 is connected to a terminal strip 32 of a switch block 33. The switch block 33 is fastened to an inner wall surface of the part 10 and is controlled by switch button 33a which projects from the part 10 as suggested in FIGS. 1 and 2. A second terminal strip 34 on the switch block 33 is electrically connected to a terminal arm 35 which is in turn connected to a tubular conductor member 36.

The tubular conductor member 36 is reclined in a bushing 38 and is internally threaded for being engaged about the threaded terminal post 6. At the upper end of the tubular conductor 36 is fixed an insulating cap 40 and by turning this cap, the threaded conductor may be solidly engaged with the post 6, thus tending to secure one side of the part 10 to the upper flanged edge of the battery 2. Similarly, a second threaded tubular conductor 42 is supported in a bushing 44 and has fixed at its upper end an insulating cap 46 by means of which the tubular conductor 42 may be solidly engaged with the terminal post 8.

When the two threaded tubular conductors 36 and 42 are firmly threaded on the respective terminal posts 6 and 8, an electrical circuit may be completed through the battery and bulb 24 with the switch 33a in a closed position.

In accordance with a further preferred embodiment of the invention, I form the upper ends of tubular conductors 36 and 42, together with their respective caps 40 and 46 with openings into which may be received two electrical contacts 48 and 50 of the signal accessory light A as shown in FIG. 3. When the electrical contacts 48 and 50 are firmly inserted, they make an electrical contact through the respective tubular conductors 36 and 42 and, thus provide a path along which current may flow from the battery to the flasher bulb A2 of the light A.

The electrical contact 50 is, moreover, solidly secured to a bracket 52 which is solidly fastened to an inner face of the light A in a position such that with contact 50 engaged in cap 46, the bracket may support the light A in an overhanging position on the part 10 as disclosed in FIG. 1.

With the arrangement described, therefore, it will be seen that I have provided, through a simple combination of fastening screws, a means for locking the light source unit on to the battery and, at the same time, provided for one electrical circuit which is under the control of the switch 33a. Moreover, the flasher unit may be either used or disconnected without in any way interfering with the operation of the main light bulb 24.

To facilitate handling the portable lamp unit described, I may provide supporting ring elements as 60 and 62 through which are received a handle 64.

As will be apparent from an inspection of FIG. 3, by merely loosening caps 40 and 46 and disengaging them from posts 6 and 8, the entire light source unit may be grasped by the handle 64 and lifted away from the battery to provide for battery replacement, storage, or other purposes.

In FIGS. 5 and 6 I have illustrated a modified form of warning light which is designed to be placed on the highway or other desired locality at some little distance from the battery. In this form of light, a cylindrical base 70 is provided with a flat base for supporting a lamp 72 of the flasher type in a stable, upright position. A bulb 72a is fitted into an electrical cable enclosure 74 detachably secured in the base 70. A cable 76 is fitted at its ends with electrical contact pins 78 and 80 which are adapted to be engaged in the battery terminals 40 and 46. When not in use, the cable 76 may be wound upon itself by turning the enclosure 74a by coiling the cable upon itself with the enclosure 74 removed. There is thus provided a compact and efficient warning light accessory which can be placed at some distance from the battery when illumination is desired at one point and a warning light is desired at another point.

While I have shown a preferred embodiment of the invention, it should be understood that changes and modifications may be resorted to within the scope of the appended claims.

Having thus described my invention, what I claim is:

1. In a portable hand light construction, a battery member having a pair of terminals projecting upwardly from the top surface thereof in spaced-apart relationship, a terminal enclosure body mounted at the said top surface of the battery, a lighting unit supported at one side of the enclosure body, a pair of fastener members for engaging with the battery terminals and detachably securing the enclosure body against the top surface of the battery, each of said fastener members presenting an upper exposed cap portion of electrical insulating material and a lower engaging portion of electrically conductive material, means for electrically connecting the said lighting unit to one of said lower engaging portions of electrically conductive material, and an electrical switch

located externally on the enclosure body for selectively controlling flow of current from the said battery through the fastener means and lighting unit.

5 2. A structure as defined in claim 1, in which each of the exposed cap portions is constructed with a reduced barrel portion extending through the enclosure body and received in a tightly fitted bushing, and each of said lower engaging portions of electrically conductive material are secured in the lower extremities of respective bushings.

15 3. A structure as defined in claim 1, including a flasher light assembly detachably supported on the enclosure body and electrically connected to the said battery terminals through said fastener means whereby the flasher light assembly may be energized independently of said electrical switch.

4. In a portable hand light construction, a battery member having a pair of spaced-apart threaded terminals projecting upwardly from the top surface thereof in spaced-apart relationship, a terminal enclosure body mounted at the said top surface of the battery in overhanging relationship therewith, a spot light apparatus supported in a laterally extending position at one side of the terminal enclosure body, threaded fastener means 25 for engaging with the said threaded terminals and detachably securing the enclosure body against the top surface of said battery, said threaded fastener means consisting of a pair of thumb nuts, each of said thumb nuts presenting an upper exposed cap portion of electrical insulating material and an electrically conductive lower portion, an electrical switch terminal block secured within the enclosure body and electrically connected to one of said electrically conductive lower portions of the thumb nuts and to said spot light apparatus, an electrical switch located externally on the enclosure body for selectively controlling flow of current from said battery through the said thumb nuts and said spot light apparatus.

40 5. A structure according to claim 4, in which the said electrically insulated cap portion of the thumb nuts are formed with central openings communicating with respective electrically conductive lower portions thereby to provide receptacles for receiving electrical conductor elements and furnishing current from the battery independently of said switch and switch terminal block.

45 6. A structure as defined in claim 2, including a flasher light unit, bracket means attached to the flasher light for supporting the flasher light upon the enclosure body and electrical conductor means for engaging through said openings in the thumb nuts and energizing said flasher light unit.
